[57] CLAIM

We claim the ornamental design for the automobile antenna, as shown and described.

DESCRIPTION

FIG. 1 is a front elevational view of an automobile antenna showing our new design with the antenna element in a collapsed (hidden) position;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a front elevational view thereof with the antenna element in an extended (visible) position.

The telescoping portion shown in broken lines in FIG. 7 is for illustrative purposes only and forms no part of the claimed design.
